(57) CLAIM

The ornamental design for a running vest as shown and described.

DESCRIPTION

FIG. 1 is a perspective view of a running vest showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The lighter-weight dash-dot broken lines in the drawings depict portions of the running vest that form no part of the claimed design. The heavier-weight dashed lines depicting lines of stitching form a part of the claimed design.
